UNITED STATES PATENT OFFICE.

WILLIAM HIGGINS, OF PHILADELPHIA, PENNSYLVANIA.

CONVERTIBLE CHAIR.

1,177,033.

Specification of Letters Patent. Patented Mar. 28, 1916.

Application filed December 23, 1914. Serial No. 878,807.

To all whom it may concern:

Be it known that I, WILLIAM HIGGINS, a citizen of the United States, residing at Philadelphia, in the county of Philadelphia and State of Pennsylvania, have invented 5 certain new and useful Improvements in Convertible Chairs, of which the following is a specification.

My invention relates to improvements in 10 convertible chairs, the object of the invention being to provide an improved device of the character stated which may be utilized as a chair, as a couch, or bed, and as a table with stools provided for seating the occu- 15 pants at the table.

A further object is to provide a convertible chair having a back which may be inclined at any angle when in use as a chair, which may be positioned horizontally when 20 in use as a bed or couch, or when in use as a table, and provide stools connected to hinged bars, which latter operate as rungs of the chair when the stools are not in use.

A further object is to provide an improved 25 device of the character stated which is neat and attractive in appearance, and which is capable of a wide range of utility as a piece of household furniture.

With these and other objects in view, the 30 invention consists in certain novel features of construction and combinations and arrangements of parts as will be more fully hereinafter described and pointed out in the claims.

35 In the accompanying drawings: Figure 1 is a view in side elevation illustrating my improved convertible chair. Fig. 2 is a view in vertical longitudinal section through the center of the chair, the view being on an appreciably larger scale than Fig. 1. Fig. 40 Fig. 3 is a broken plan view partly in section illustrating my improved device when in use as a table. Fig. 4 is a fragmentary view in side elevation of the parts as shown in Fig. 45 Fig. 3, and Fig. 5 is a view in side elevation illustrating my improved device in operative position as a couch.

1 represents the seat of the chair supported by four legs 2.

50 3 represents the arms of the chair which are connected by hinges 4 with uprights 5, the latter connected by hinges 6 with the seat 1, so that these arms are permitted to swing downwardly and rearwardly when

permitted by filler pieces 7. These filler 55 pieces 7 are normally under the arms 3 between the uprights 5, and at their lower ends are connected by hinges 8 with the seat, so that whenever desired, these filler pieces may be swung outwardly and downwardly to allow the arms to move rearwardly and downwardly as shown in Fig. 5.

9 represents the back of the chair which is provided at its lower edge with metal plates 10 mounted to swing in recessed brackets 11 65 secured to the seat 1. The back 9 is cut out or recessed to accommodate the ends of the bracket 11, and by reason of this construction the back can be pivoted to or removed from the brackets as occasion may require. 70

The arms 3 of the chair are provided at their rear ends with slotted plates 12, and back of the plates, the arms are recessed as shown at 13 to accommodate rods 14, said rods being pivotally connected to the chair 75 back 9 by means of rivets 15, connecting the said rods to couplings 16 which are T-shape and move in longitudinal grooves 17 in the walls of back 9. The rods 14, at their forward ends, are provided with laterally projecting screw-threaded lugs 18 which have circular thumb nuts 19 on their outer ends. These thumb nuts may be tightened and loosened to permit the adjustment of the back and to prevent any accidental movement, the outer faces of the plates 12 are provided with enlargements 20, between 80 which the thumb nuts 19 may be located and prevent any accidental longitudinal movement of the rods after they are once 90 adjusted.

21 represents a removable support which is adapted to be positioned at the front of the chair seat. This support 21 may, of course, be connected in various ways. I 95 have illustrated as a simple form of connection, in order to explain my invention, dowel pins 22 on the support which engage in recesses 23 in the seat. One side of the support is provided with a cushion 24 which 100 is uppermost when the support is at the front of the chair seat, and which is lowermost when the support is stored beneath the seat. When this support is not desired for use, it is located in guides 21^a under the 105 seat, so that it is out of sight and out of the way.

25 represents the cushion for the seat, and

26 represents the cushion for the back of the chair. These cushions are preferably connected so that while they are free to move relative to each other, they can be removed 5 and remain together.

5 The chair legs 2 are connected by rungs 27. These rungs are secured at one end to the legs by hinges 28, and at their other ends are provided with hasps 29 which receive staples 30 on the legs of the chair, and are secured by hooks 31. By reason of 10 this construction, each of the rungs is capable of swinging outwardly from the chair and at the free end of each rung, I provide a hinged arm 32, and at the free end of each hinged arm, I provide a stool 33. These 15 stools are preferably of the type indicated with adjustable seats 34 having screws 35 engaging the standards of the stool.

20 When the device is in use as a chair, all of the rungs 27 will be as shown in Figs. 1 and 2, that is to say, the arms 32 are folded inwardly and the free ends of the rungs are secured by means of the hasps 29 25 as above described. When the device is to be used as a couch, the filler pieces 7 are swung downwardly, and the back 9 is lowered to a horizontal position. When in this position, the rear rung 27 is swung 30 outwardly, and the stool 33 carried thereby is positioned under the back 9 to support the same. Also, when in use as a couch, the support 21 is positioned at the forward end of the seat 1 as clearly shown in Fig. 5. 35 When the device is to be used as a table, the back 9 is detached from the brackets 11 and swung downwardly upon the arms 3, so that it assumes a horizontal position as shown clearly in Figs. 3 and 4. When in this position, the several rungs 27 are swung outwardly, and the stools positioned to receive 40 their occupants.

45 Various slight changes might be made in the general form and arrangement of parts described without departing from my invention, and hence I do not limit myself to the precise details set forth, but consider myself at liberty to make such changes and alterations as fairly fall within the spirit and 50 scope of the appended claims.

Having thus described my invention, what I claim as new and desire to secure by Letters Patent is:

1. A convertible chair comprising a seat, 55 a back adapted to be positioned above the seat to form a table top, legs supporting the seat, rungs having hinged connection at one end to certain of the legs respectively and removable connection at their other 60 ends to other of said legs, and stools connected to said rungs, substantially as described.

2. A convertible chair comprising a seat, arms on the seat, a back adapted to be positioned on the arms to form a table top,

legs supporting the seat, rungs having hinged connection at one end to certain of the legs respectively and removable connection at their other ends to other of said legs, arms hinged to the free ends of the rungs, 70 and stools connected to the free ends of the arms, substantially as described.

3. A convertible chair comprising a seat, legs supporting the seat, uprights hinged to the seat, arms hinged to the uprights to 75 move rearwardly therefrom, a chair back removably and pivotally connected at its lower end to the seat, devices adjustably connecting the back with the arms, and filler pieces adapted to be positioned under the 80 arms to hold the latter against rearward and downward movement, substantially as described.

4. A convertible chair comprising a seat, legs supporting the seat, uprights hinged to the seat, arms hinged to the uprights to 85 move rearwardly therefrom, a chair back removably and pivotally connected at its lower end to the seat, devices adjustably connecting the back with the arms, filler 90 pieces hinged to the sides of the seat and when in an upright position, located under the arms and adapted to be swung downwardly to permit the arms and back a downward and rearward movement to change the 95 chair into a couch, substantially as described.

5. A convertible chair comprising a seat, legs supporting the seat, uprights hinged to the seat, arms hinged to the uprights to move rearwardly therefrom, a chair back removably and pivotally connected at its lower end to the seat and adapted to be positioned on the arms to form a table, devices adjustably connecting the back with the arms, filler pieces hinged to the sides of 100 the seat and when in an upright position, located under the arms and adapted to be swung downwardly to permit the arms and back a downward and rearward movement to change the chair into a couch, substantially as described. 110

6. A convertible chair comprising a seat, arms on the seat, a back connected to the 120 seat and adjustably connected to the arms, said back adapted to be positioned upon the arms to form a table, rungs connecting the legs of the chair, said rungs connected at one end by hinges, and at their other ends having hasps adapted to receive staples secured to the legs, hooks on the hasps adapted to be positioned through the staples, arms pivotally connected to the free ends of the 125 rungs and adapted to be positioned under 130

the chair seat, and stools connected to the free ends of said rungs, substantially as described.

7. A chair comprising a seat, legs supporting the seat, movable arms connected to the seat, devices movably connected to the seat and adapted to support the arms in normal position, a movable back adapted to be positioned on the arms to form a table, 10 rungs hinged to certain of the legs respec-

tively and removably connected to other of the legs, and stools connected to said arms, substantially as described.

In testimony whereof I have signed my name to this specification in the presence of 15 two subscribing witnesses.

WILLIAM HIGGINS.
